UNITED STATES PATENT OFFICE

159,198

AIRPLANE

Marvin H. Greenwood and Lomis Slaughter, Jr.,
Houston, Tex.

Application March 26, 1949, Serial No. 1,654

Term of patent 14 years

(Cl. D71—1)

To all whom it may concern:

Be it known that we, Marvin H. Greenwood and Lomis Slaughter, Jr., both residing at Houston, in the county of Harris and State of Texas, have invented a new, original, and ornamental Design for an Airplane, of which the following is a specification, reference being made to the accompanying drawings, forming part thereof, the present application comprising a continuation-in-part of our copending application Serial No. D. 138,988, filed May 12, 1947, and now abandoned;

Figure 1 is a top plan view of an airplane embodying the new design;

Fig. 2 is a front elevational view thereof;

Fig. 3 is a side elevational view thereof;

Fig. 4 is a perspective view from above and from the rear of the airplane, partly broken away for convenience of illustration;

Fig. 5 is a cross-section taken along line 5—5 of Fig. 4.

The characteristic features of our design reside in the portions shown by means of full lines in the drawing.

We claim:

The ornamental design for an airplane, substantially as shown and described.

MARVIN H. GREENWOOD.
LOMIS SLAUGHTER, JR.
